WITNESS:

UNITED STATES PATENT OFFICE.

LESLIE R. KIEHL, OF RATON, NEW MEXICO.

LOCOMOTIVE-FLANGE OILER.

Application filed August 2, 1924. Serial No. 729,776.

To all whom it may concern:

Be it known that I, LESLIE R. KIEHL, a citizen of the United States, residing at Raton, in the county of Colfax and State of New Mexico, have invented new and useful Improvements in Locomotive-Flange Oilers, of which the following is a specification.

This invention relates to lubricating devices, and has for its object the provision of a novel pressure operated device for supplying oil to the flanges of the drivers of a locomotive.

The essential feature is the provision of a device of this character which is connected with the exhaust steam line whereby the proper pressure will be developed for forcing oil from a reservoir and supplying it to the wheel flanges.

Another object is the provision of a device for this purpose in which the proper pressure will be automatically maintained, means being, however, provided whereby the pressure may be varied.

Yet another object is the provision of a peculiar arrangement designed to prevent damage by freezing of the water of condensation.

With the above and other objects and advantages in view, the invention consists in the details of construction and arrangement of parts to be hereinafter fully described and claimed, and illustrated in the accompanying drawings, in which:—

Figure 1 is a somewhat diagrammatic side elevation of a locomotive equipped with my device.

Figure 2 is a view on the line 2—2 of Figure 1 looking downwardly.

Figure 3 is a vertical section through the device.

Figure 4 is a section on the line 4—4 of Figure 3.

Figure 5 is a section on the line 5—5 of Figure 3.

Figure 6 is a detail section through the pressure control valve.

Referring more particularly to the drawings, the letter A designates a locomotive having the driver wheels B which are to be lubricated. In carrying out my invention I provide an automatic oiling device which includes a casing 10 constituting a reservoir for oil and upon which is mounted a second casing 11 which constitutes a mixing chamber as will be explained. The two casings are here represented as detachable and con-

nected by threaded flanges 12 and 13, but may be cast in suitable form if preferred. The casing 10 is provided with a drain valve 14 and filling plug 15, while the casing 11 has a suitable cap 16.

Within the casing 10 is a pipe coil 17 having several convolutions and having one end 18 terminating somewhat above the center of the casing 10. Connected with or formed integrally upon the other end of this coil is a tube 19 which extends through a hole 20 in the bottom of the casing 11 and which is surrounded by an upstanding pipe 21 defining a chamber or air space 22 about the tube 19 for permitting expansion, without damage, in case the contents of the casing 10 freeze. The top of the pipe 21 is closed except for a small hole within which the upper end of the tube 19 is secured.

The device is used in connection with the exhaust line 23 of the locomotive and I have shown the casing 11 as provided with inlet and outlet pipes 24 and 25, respectively, the latter of which has connected therewith branches 26 which lead to the flange of the wheels B for supplying them with oil. The inner end of the pipe 24 is inclined or otherwise formed to define a seat 27 for a flap or other suitable valve 28 carried by an arm 29 pivoted at 30 at the top of the casing 10. The top of the casing 10 is formed with a hole 31 adapted to be closed by a valve 32 which has its stem 33 engaged by the arm 29 so that the position of the arm 29 will govern the degree of opening of the valve 32.

For adjusting the throw of the lever 29, I provide an elongated screw 34 threaded through a boss 35 on the top of the casing 11. The upper end of this screw carries a head 36 while its lower end is so positioned as to be engaged by the lever 29 for limiting opening movement of the valve 28 and thereby controlling the entrance of steam to the casing 11.

Interposed in the pipe 24 is a casing 37 within which is mounted a valve 38 having a conical top 39 adapted to engage a seat 40. The valve is formed with passages 41 for permitting a limited pressure of steam to pass therethrough.

In the operation, steam passes through the pipe 24 around the valve 38 and passes into the casing 11. The inrushing steam impinging against the valve 28 lifts it and the lever 29, and also lifts the valve 32 from its seat. The casing 11 is then of course full

of steam and a certain amount passes out through the outlet pipe 25. Owing to the fact that the upper end of the pipe 19 is in communication with the interior of the casing 11 and owing to the fact that the valve 32 is unseated, leaving the opening 31 open to a great or less extent, it will be clear that while there is a pressure exerted through the pipe 19 and also upon the oil contained within the casing 10, these pressures will balance or equalize. After the steam has been passing into and through the casing 11 for a short period of time, the pipe coils 17 will become filled with water of condensation. It is of course understood that initially the casing 10 is filled with oil and it will be quite obvious that as water of condensation accumulates within the coils 17 and passes out through the discharge end 18 thereof the level of the oil will be raised and a quantity thereof will pass out through the opening 31 and be mixed with the steam in the casing 11 and discharged therewith through the pipe 25 and pipes 26 to the flanges of the wheels to be oiled. When the device is first set in operation it is quite clear that some short time will be necessary in order to permit the water of condensation to accumulate within the coils 17 to a sufficient extent to raise the oil level and effect discharge of the oil to the wheel flanges. However, after the initial starting it is quite evident that even the accumulation of one or two drops or any other small quantity of water of condensation will raise the oil level within the casing 10 to a corresponding degree and the outlet of oil will be consequently automatic in accordance with this action.

After the device has been in use for sometime the amount of oil remaining within the casing 10 and floating upon the body of water of condensation accumulated therein will be continually decreased. In order that the oil supply may then be replenished the valve 14 is opened to permit draining of the water and the filling plug 15 is removed so that additional oil may be poured into the casing 10 to bring the supply up to normal. When draining of the water is effected it will be seen that it is impossible to drain the coils 17 and it is intended that these coils be left substantially full of the water of condensation to avoid delay in the operation when subsequent use is desired. The rate of flow of oil is of course governed by the position of the arm 29 controlling the valve 32 and the position of this arm is in turn controlled by the adjustment of the screw 34 which limits the movement of the arm and the degree of opening of the valve 28 controlling the pressure of steam.

Even in severe weather it is apparent that there is little danger of freezing of any of the essential parts inasmuch as the coils 17

are enclosed within the body of oil in the casing 10 and as the pipe 19 is enclosed within an air chamber. However, if the contents of the casing 10 should freeze, and consequently expand this expansion is taken care of as the air within the chamber 22 may compress and consequently permit expansion without breakage of any of the parts.

If the steam pressure should become excessive, the valve 38 will engage against its seat 40, cutting off communication through the pipe 24 except that the passages 41 will still permit a limited amount of steam to pass.

From the foregoing description and a study of the drawings it will be apparent that I have thus provided a very simple automatic device for the purpose specified which will operate on the hydrostatic principle and controlled by an easily regulable steam pressure. Ample provision has been made for effecting all necessary adjustment and the parts are all so constructed and correlated as to insure positive and efficient action.

While I have shown and described the preferred embodiment of the invention, it should be understood that I reserve the right to make such changes in the form, construction and arrangement of parts as will not depart from the spirit of the invention or the scope of the subjoined claims.

Having described the invention, I claim:—

1. A device of the character described comprising a pair of casings arranged one above the other, the lower casing serving as an oil reservoir, a condensation coil arranged vertically within the lower casing and having one end terminating therein and its other end leading into the upper casing to convey steam from the upper casing to the lower casing to displace oil therefrom, a pipe leading from the upper casing and terminating in branches leading to the locomotive wheels to be oiled, a control valve between the casings for the passage of the displaced oil, a steam pipe leading into the upper casing, and means operated by flow of steam through said pipe to regulate said valve.

2. A device of the character described comprising a pair of casings arranged one above the other, the lower casing serving as an oil reservoir, a condensation coil arranged vertically within the lower casing and having one end terminating therein and its other end leading into the upper casing to convey steam from the upper casing to the lower casing to displace oil therefrom, a pipe leading from the upper casing and terminating in branches leading to the locomotive wheels to be oiled, a control valve between the casings for the passage of the

displaced oil, a steam pipe leading into the upper casing, and means operated by flow of steam through said pipe to regulate said valve; said means including a lever pivoted 5 within the upper casing and resting upon said valve, and a valve plate at the end of said lever positioned to have the inrushing steam impinged thereagainst.

3. A device of the character described 10 comprising a pair of casings arranged one above the other, the lower casing serving as an oil reservoir, a condensation coil arranged vertically within the lower casing and having one end terminating therein and 15 its other end leading into the upper casing to convey steam from the upper casing to the lower casing to displace oil therefrom, a pipe leading from the upper casing and terminating in branches leading to the locomotive wheels to be oiled, a control valve 20 between the casings for the passage of the displaced oil, a steam pipe leading into the upper casing, and means operated by flow of steam through said pipe to regulate said 25 valve; said means including a lever pivoted within the upper casing and resting upon said valve, and a valve plate at the end of

said lever positioned to have the inrushing steam impinged thereagainst; and a screw threaded through the top of the upper casing and engageable by said valve plate for limiting the movement thereof. 30

4. A device of the character described comprising a pair of casings arranged one above the other, the lower casing serving as 35 an oil reservoir, a condensation coil arranged vertically within the lower casing and having one end terminating therein and its other end leading into the upper casing to convey steam from the upper casing to 40 the lower casing to displace oil therefrom, a pipe leading from the upper casing and terminating in branches leading to the locomotive wheels to be oiled, a control valve between the casings for the passage of the 45 displaced oil, a steam pipe leading into the upper casing, and means operated by flow of steam through said pipe to regulate said valve, and a pipe within the upper casing surrounding the second named end of the 50 coil to form an air chamber thereabout for preventing damage by freezing.

In testimony whereof I affix my signature.
LESLIE R. KIEHL.
